EMBOSSING PRESS

Original Filed Nov. 10, 1921 3 Sheets-Sheet 3

UNITED STATES PATENT OFFICE.

EDWARD E. POLLOCK, OF LOS ANGELES, CALIFORNIA, ASSIGNOR, BY MESNE ASSIGNMENTS, TO HULSE MANUFACTURING COMPANY, OF GENEVA, NEW YORK, A CORPORATION OF NEW YORK.

EMBOSSING PRESS.

Application filed November 10, 1921, Serial No. 514,360. Renewed June 12, 1923.

To all whom it may concern:

Be it known that I, EDWARD E. POLLOCK, a citizen of the United States, and resident of Los Angeles, in the county of Los Angeles and State of California, have invented certain new and useful Improvements in Embossing Presses, of which the following is a specification.

This invention relates to improvements in embossing presses, and more particularly to presses for forming signs, advertising cards, and the like by punching characters from paper and forcing the same into a sheet of cardboard or other backing of contrasting color.

The invention has for its principal objects to provide a simple and efficient type-holding means for the press; to provide means for holding lines of type in variably spaced relation; to provide independently adjustable and removable holders for lines of type; to provide type holding means shiftable to afford unobstructed access to the paper-supporting surface; and to provide means for bodily shifting the set-up type between the pressure heads of the press.

To the foregoing and other ends, which will hereinafter appear, the invention consists in the features of construction, arrangements of parts and combinations of devices set forth in the following description and particularly pointed out in the appended claims.

In the accompanying drawings,

Figure 1 is a vertical sectional view on the line 1—1 of Fig. 2;

Fig. 2 a plan view of the press, a part of the upper head thereof being broken away;

Fig. 3 a central longitudinal section of the type-carrying frame, showing the hinged portion thereof swung partly upward;

Fig. 4 a detail perspective view of a portion of the type-carrying frame;

Fig. 5 a sectional view of the type-carrying frame, taken on the line 5—5 of Fig. 2;

Fig. 6 a vertical transverse section of the press, taken on the line 6—6 of Fig. 2, show-

ing the parts ready for the squeezing operation;

Fig. 7 a fragmentary sectional view showing the type pressed into the paper and cardboard;

Fig. 8 a central longitudinal sectional view of one of the independently removable and adjustable holders for lines of type;

Fig. 9 a bottom plan view of one of the type-holders;

Fig. 10 a section on the line 10—10 of Fig. 8;

Fig. 11 a section on the line 11—11 of Fig. 8;

Fig. 12 a section on the line 12—12 of Fig. 8;

Fig. 13 a section on the line 13—13 of Fig. 8; and

Fig. 14 a transverse sectional view showing a slightly modified form of type and paper supporting means, the section being taken on the same line as Fig. 6.

The main frame 20 of the press is of box-like form, and a stationary platen or press-head 21 is held above the frame on four vertical posts 22, the platen being clamped between sleeves 23 on said posts and nuts 24 threaded on the upper ends of the posts. A vertically reciprocable pressure head 25 is guided in the upper end of frame 20 and is movable toward and from the platen 21 by a rotatable cam bar 26 extending through the frame. Flanged bushings or collars 27 and 28 keyed on opposite ends of cam bar 26 work in vertically elongated bearing apertures 29 formed in the side walls of the frame 20, the bushing 28 being formed with a tubular extension or lever socket 30 in which one end of a handle or press-operating lever 37 is inserted. Thrust plates 31 and 32 engage opposite sides of the cam bar. A cage 33 containing antifriction rollers 34 is interposed between plate 31 and the bottom wall of the frame 20, while a similar cage 35 containing antifriction rollers 36 is interposed between plate 32 and pressure head 25. The wider flat sides of bar 26 nor-

2
mally engage plates 31 and 32, and it will be obvious that when lever 37 is rocked toward the left, as viewed in Fig. 1, the cam bar will force head 25 upwardly toward the platen 21. The parts above described are constructed and arranged substantially as shown and described in my prior Patent No. 1,168,740, granted January 18, 1916, the present improvements consisting in the provision of the type and paper supporting means hereinafter described.

Countersunk in the top face of the press head 25 is a rigid bar 38, held to the head by screws 39 and projecting beyond both the forward and rear edges of the head. Bar 38 is relatively long and preferably projects considerably farther from the forward edge of head 25 than from the rear edge. A metal plate 40 is held to bar 38 and head 25 by screws 41, said plate extending from end to end of the bar and having upstanding side flanges 42 along its longitudinal edges only. Plate 40 is preferably as wide transversely as head 25 and forms a trough-like table 25 movable up and down with press head 25 and open at both ends.

A sliding and swinging type-carrying frame is provided, said frame comprising side bars 43 and 44, a front crossbar 45 formed with a handle 46, and a rear crossbar or pivot rod 47. Said frame may be slidably and pivotally supported on the table 40 in various ways to adapt the same to be slid between the press heads or to be slid out from between said heads and then swung upward away from the table. In the construction shown, the ends of rod 47 are journaled in vertically elongated bearing apertures 48 adjacent the rear ends of the side bars 49 of a U-shaped slidable support or frame removably and slidably mounted on and guided in the trough-like table, said slides or bars 49 being rigidly connected at their rear ends by a cross-bar 50. Slides 49 rest on the bottom of table 40 and engage the side flanges 42 of the table, said slides being higher than the flanges 42.

The cross-bar 50 and the rod 47 are above the bottom of the slides 49 and above the table to leave the rear end of the table free and unobstructed. This permits the work sheet to be moved rearwardly over the table and beyond the rear open end thereof so that sign sheets longer than the type carrying frame may be used.

The side bars 43 and 44 of the swinging frame are provided with inwardly facing grooves or channels 51 and 52, respectively, the lower sides of which are serrated, as shown, and bar 44 is provided with a top section or plate 44^a hinged at 53 to swing upwardly to uncover channel 52. Plate 44^a is adapted to be locked at its forward end to the main section of bar 44 by a spring clip or latch 54.

The press is adapted for use with sets or fonts of embossing type of various sizes and styles, said type comprising blocks 55 having the usual cutting type faces, and each block is provided along its top and bottom edges with flanges or lateral projections 56 adapted to engage in the inwardly facing channels 57 formed along the longitudinal edges of the metallic type-holding bars 58. Each type-holder 58 has its longitudinal edges rolled laterally and then inwardly to form the channels 57 and is provided with flat end portions 59 adapted to engage in grooves 51 and 52 in bars 43 and 44, the under faces of said end portions 59 being serrated. Sets of type-holders 58 of various widths are provided for holding lines of type of different sizes, as shown in Figs. 1 and 2, and any desired number of type-holders within the capacity of the frame may be inserted in the swinging frame.

The operation is as follows:

The type 55 forming each line of reading matter are slid endwise into a type-holder 58 and are held in the desired position in the holder by sliding blocks 60 adapted to be locked in place by set screws 61. It will be understood, of course, that a plurality of groups of type may be held in a single type holder by inserting additional blocks 60 in the holder. The type holders are inserted in the swinging frame in the desired spaced relation by passing one end 59 into groove 51 in bar 43 and lowering the other end 59 into groove 52 in bar 44, and are then locked in place by swinging down the top section 44^a of bar 44 and locking said section in place by means of latch 54. The serrated edges of the end portions 59 of the holders are thus locked in engagement with the serrated edges of the grooves 51 and 52 and relative movement of the holders is thereby prevented. The swinging frame is swung upward and rearward, as shown in dotted lines in Fig. 1, and the sheet of cardboard 62 is placed upon the forward portion of table 40. A sheet of colored paper 63 is then laid upon the sheet of cardboard. If a multi-colored sign or the like is to be made, pieces of different colored paper will be laid over the proper portions of the cardboard sheet in position to be engaged by the different groups of type. The type-carrying frame is then swung down until the type rest on the paper. If the paper or cardboard is not properly adjusted with relation to the type the fact will be obvious when the frame is lowered and proper adjustment may be made by again lifting the frame and shifting the paper or cardboard, or both. When proper registration is obtained the cardboard, paper, sliding frame 49-50, and the swinging frame are all slid rearward in unison under the platen 21, and

handle 37 is pulled forward to elevate head 25 and press the cutting faces of the type through the colored paper and into the cardboard sheet, thus cutting out characters 5 from the colored paper and forcing them into the cardboard sheet. In making large signs a plurality of successive pressing operations are necessary, the frames and paper being slid rearward step by step to successively position groups of type holders under head 21. When the pressing operation, or operations, is completed the frame 49-50, the swinging type-carrying frame, and the cardboard and colored paper sheets 10 are pulled forward from beneath head 21, the type-carrying frame is swung upwardly, and the surplus colored paper is stripped from the cardboard sheet.

The platen 21 is formed with a raised surface 21a at its under side adapted to pass between the bars forming the swinging frame and press against the upper faces of the type-holders 58. The loose pivots 48 permit relative downward movement between the hinged end of the type-carrying frame and slides 49 when pressure is applied to the type-holders. Slides 49 are adapted to engage the platen 21 to limit the upward movement of head 25 and table 40 and thereby prevent the type from being accidentally forced entirely through the cardboard sheet. Any other suitable means may be provided for this latter purpose, for example, fixed or adjustable stops may be provided on head 21 adapted to engage the table 40 or a part of head 25. By providing removable holders for lines or groups of type, frequently used matter may be left set-up in holders and stored for use when desired, thus avoiding the labor of re-setting type for such matter at frequent intervals.

In Fig. 14 a slightly modified construction is shown in which a flat metal bottom plate 64 is nailed or otherwise fastened to the under sides of slides 49, said plate extending from end to end of the slides and forming a sliding support for the cardboard and colored paper sheets. In this construction said sheets are clamped between the plate 64 and the type in the type-carrying frame during the sliding thereof rearward under the platen 21.

It will be obvious that signs, notices, or the like of any desired length may be formed 55 with an apparatus constructed as above described by advancing a long sheet through the press step by step and changing the type in the frame as successive portions of the sign are embossed.

60 What I claim is:

1. The combination with an embossing press, of a type-carrying support pivotally and slidably held to the bed thereof.

2. An embossing apparatus comprising 65 relatively reciprocable squeezing members,

and a type carrier pivotally and slidably held to one of said members to swing toward and from said member and slide into and out of position between the members.

3. An embossing apparatus comprising a 70 bed, a platen, means for imparting relative movement between the bed and platen, a type-carrier slidable transversely of the bed into and out of position under the platen and rockable away from said bed, and type 75 holders removably held to said carrier.

4. An embossing apparatus comprising a bed, a platen, means for imparting relative movement between the bed and platen, a type-carrier slidable transversely of the bed 80 into and out of position under the platen and rockable away from said bed, and type holders removably and adjustably held to said carrier.

5. An embossing apparatus comprising a 85 bed, a platen, means for imparting relative movement between the bed and platen, a type-carrier slidable transversely of the bed into and out of position under the platen and rockable away from said bed, type 90 holders removably and adjustably held to said carrier, and type adjustably mounted in said type-holders.

6. An embossing apparatus comprising a bed, a platen, means for imparting a relative 95 vertical movement between the bed and platen, a support slidable transversely of the bed, and a type-carrying frame pivotally held at one end to said support to swing toward and from the bed. 100

7. An embossing apparatus comprising a bed, a platen, means for imparting a relative vertical movement between the bed and platen, a support slideable horizontally on the bed, a frame pivotally held at one end to 105 said support to swing toward and from the bed, and type holding means removably held in the frame.

8. An embossing apparatus comprising a bed, a platen, means for imparting a relative 110 vertical movement between the bed and platen, a support slideable horizontally on the bed, a frame pivotally held at one end to said support to swing toward and from the bed, a plurality of independently removable type-holders adjustably mounted in the frame, type removably and adjustably mounted in said holders, and means for locking the type in their adjusted positions in the holders. 115

9. An embossing apparatus comprising a bed, a platen, means for imparting a relative vertical movement between the bed and platen, a support slideable horizontally on the bed, a frame pivotally held at one end to said support to swing toward and from the bed, said support being adapted to engage the platen to limit the movement of the bed and platen toward each other, and type-holding means 125 carried by the frame. 130

10. A type-carrier for embossing presses comprising a slidable support, a frame pivotally held to said support, and type-holding means carried by said frame.
- 8 11. A type-carrier for embossing presses comprising a slidable support, a frame pivotally held to the support, removable type-holding devices, and means for securing the type-holding devices to the frame in various 70 adjusted positions.
- 10 12. A variable type-form holder for embossing presses comprising a support having inwardly facing channels along two parallel sides thereof, and a plurality of type-holders 75 extending transversely of said support each having two toothed end portions engaging in said channels, each of said channels having transverse notches throughout the length of one side wall thereof adapted 80 to receive the teeth on the end portions of the type-holders in various adjusted positions of the holders on said support, and each type-holder having edge flanges between its toothed ends formed with inwardly facing channels.
13. In an embossing apparatus, the combination of a bed, a platen, means for imparting relative vertical movement between the bed and platen, a support slidable on the bed between the bed and platen and adapted to limit the movement of said bed and platen toward each other, and type-carrying means having a loose pivotal connection at one end with said support.
- 30 14. In an embossing apparatus, the combination of a bed, a platen, means for imparting relative vertical movement between the bed and platen, a tray-like sheet-holder 85 slidable on the bed, and a type-carrying frame pivotally connected at one end with said sheet-holder.
- 40 15. An embossing device comprising a work-sheet engaging member having an inner work-sheet engaging surface, a type-carrying frame, means pivotally connecting 90 said member and frame adjacent one end to swing toward and from each other, said means arranged to permit a limited movement of the members toward and from each other in parallelism while in superposed relation, and type held to said frame in position to have the faces thereof cooperate with the work-sheet engaging member to clamp the work when the member and frame are 95 swung into superposed relation.
- 50 16. An embossing device comprising a work-sheet engaging member having an inner work-sheet engaging surface, a type-carrying frame, means pivotally connecting 100 said member and frame adjacent one end to swing toward and from each other, said means arranged to permit a limited movement of the members toward and from each other in parallelism while in superposed relation, type held to said frame in position 105 to have the faces thereof cooperate with the work-sheet engaging member to clamp the work when the member and frame are 110 swung into superposed relation, and means for squeezing the frame and sheet-engaging member to force the type into a clamped work sheet.
17. In an embossing apparatus, the combination of a platen, a relatively long bed projecting laterally substantial distances 75 beyond two opposite edges of the platen, means for imparting relative vertical movement between the bed and platen, a type holder, and means for supporting said holder for sliding movement longitudinally 80 of the bed and pivotal movement toward and from the bed.
18. In an embossing apparatus, the combination of a platen, a relatively long bed projecting beyond opposite edges of the 85 platen, means for imparting a relative vertical movement between the bed and platen, a support slidable longitudinally of the bed, and a type-holding frame pivotally held at one end to said support adjacent one end of 90 the support to swing up and down relatively to the bed.
19. An embossing apparatus comprising a bed, a platen, means for imparting a relative vertical movement between the bed and platen, a work-sheet support 95 slidably mounted on the bed to move into and out of register with the platen, a swinging support, type held at one face of said swinging support, and means pivotally connecting the 100 swinging support to the work-sheet support to permit the type to be swung down upon the work on the sheet support, and means permitting relative vertical movement between said supports at said pivotal connection.
20. An embossing apparatus, comprising a bed, a platen, means for moving the bed up and down, a support slidable horizontally on the bed and adapted to engage the platen 110 to limit movement of the bed toward the platen, an open type-carrying frame having a pivotal and vertical sliding connection at one end with said support, said frame having longitudinal side rails formed with inwardly facing channels having notched bottom walls, and type-holders having toothed end portions engaged in said channels and intermediate type-supporting portions, one 115 of said rails having a hinged section forming the top wall of the channel therein, and means for releasably locking said hinged rail section against opening movement, said platen having a raised surface on its under face for engaging the backs of the intermediate portions of the type holders.
21. In an embossing press, the combination of a platen, a pressure head under the platen, means for imparting relative vertical movements between said platen and head, a 120

- long work-sheet-support slidably mounted on the pressure head to move horizontally fore and aft between the pressure head and platen to present successive sections of said support, under the platen, a long type-carrying frame movable with said support, and means on said frame for supporting groups of type face down over a work sheet on the support, whereby successive groups of type 5 may be advanced between the pressure head and platen and pressed into a work sheet by successive squeezing operations of the press.
22. In an embossing press, a pair of superposed press heads, means for imparting vertical movement between said heads, a long work and type supporting carriage movable endwise horizontally between the heads to present successive sections thereof between the heads, said heads being relatively narrow 10 longitudinally of the carriage, and means for guiding said long carriage on one of said heads to move horizontally between the heads.
23. In an embossing press, a fixed platen, a vertically shiftable pressure head under the platen, means for shifting said head, a long work support movable between the platen and head to present successive areas thereof substantially equal to the surface 15 area of the platen under the platen, means for slidably holding said work support to the pressure head to move horizontally across the head, and a long type-holding frame held to said support to move horizontally therewith and to move vertically relatively thereto when squeezed between the support and platen.
24. In an embossing press, the combination of a pair of superposed relatively shiftable squeezing members relatively narrow from front to rear, a long work support 20 slidably held to the lower member to move horizontally fore and aft between said members, a long type-holding frame having a pivotal and up-and-down shiftable connection at its rear end with the support, and means on said frame for supporting type face-down over the support.
25. In an embossing press, the combination of a bed, a platen over the bed, means for imparting relative vertical movement between the bed and platen, a work support 25 slidably over the bed, a type-carrier, and means connecting the type-carrier to the support to slide therewith and permit shifting of the carrier from an inactive position affording free access to the work-supporting surface of the support to an active position overlying said surface.
26. An embossing press comprising a pair of superposed relatively shiftable pressure heads, a long combined work and type supporting carriage slidable endwise between the heads, and means for slidably supporting the long carriage on one of the heads, 30 said heads being relatively narrow longitudinally of the carriage, whereby successive groups of type and portions of work sheets may be positioned between the heads for squeezing action by successive endwise movements of the carriage.
27. An embossing press comprising a pair of superposed pressure heads, means for imparting relative vertical movements between said heads, a long work support shiftable endwise between the heads, said heads being relatively narrow longitudinally of the work support, and means slidably guiding the long work support to move horizontally over the lower head.
28. An embossing press comprising a platen, a pressure head shiftable toward and from the platen, a long work support, said platen being relatively narrow longitudinally of the support, and means holding the work support on the pressure head to slide endwise between the head and platen and to move bodily with the head toward the platen.
29. An embossing press comprising a bed, a fixed platen above the bed, means for shifting the bed vertically, and a long work and type carrier mounted on the bed to move vertically therewith and shift horizontally endwise relatively to the bed from a position out of register with the platen to present successive sections of the carrier under the platen, said platen being relatively narrow longitudinally of the carrier.
30. An embossing press, the combination of a platen, a pressure head, means for imparting relative vertical movements between said platen and head, a long carriage having a work-engaging part and a type-holding part hinged together, said platen and head being relatively narrow longitudinally of the carriage, and means slidably holding one of the hinged parts of the carriage to the head to move horizontally endwise between the platen and head.
31. In an embossing press, the combination of a pair of squeezing members, and a combined work and type support shiftable between said members and comprising a type-form holder and a flat work-engaging member connected together for relative pivotal movement into and out of parallel relation and for relative movement toward and from each other while parallel.
32. A carriage for embossing presses comprising a work support and type-form holder, and means connecting the holder at one end to the support for pivotal movement toward and from one face of the support and for up and down movement relatively to the support while parallel therewith.
33. In an embossing press, a fixed platen, a vertically shiftable pressure head under the platen, means for shifting said head, a long work support movable between the heads, and means for supporting the long carriage on one of the heads,

platen and head to present successive areas thereof substantially equal to the surface area of the platen under the platen, said work support being unobstructed at its rear end to permit the work sheet to extend beyond the rear edge of said support, means for slidably holding said work support to the pressure head to move horizontally, and a long type carrier movable with said support and provided with means for holding 10 the type face down over the support. In testimony whereof I hereunto affix my signature.

EDWARD E. POLLOCK.
